FIG. 2.

FIG. 3.

By

Arthur Friedman
Edmund J. Te Pas Attorney

UNITED STATES PATENT OFFICE

ARTHUR FRIEDMAN, OF CLEVELAND, OHIO, ASSIGNOR TO THE CLEVELAND HEATER COMPANY, OF CLEVELAND, OHIO, A CORPORATION OF OHIO

UNION CONNECTER

Application filed March 3, 1928. Serial No. 258,870.

This invention relates to storage automatic water heaters of the side arm type and in particular the connectors between the storage tank and the water circulating elements.

5 Water heaters of the above type in general include a storage tank and circulation elements which are placed in communication therewith. Operation of the heater is automatically controlled by a thermostat of the conventional type which is mounted in the tank in a tapping which is provided for this purpose. With the above arrangement three distinct threaded openings are provided in the storage tank, two for the circulation elements of the heater and one for the thermostat.

10 One of the objects of my invention is to provide a storage automatic heater in which but two tappings are necessary for reception of circulation elements of the heater and controlling thermostat.

15 Another object of my invention is to provide coupling members for placing the circulation elements of the heater in communication with the storage tank and which at the same time permit the ready removal and replacement of the circulation elements without disturbing the coupling members which connect these elements to the tank.

20 Another object of my invention is to provide a coupling member which also provides a means for reception of a thermostat.

25 In general my invention consists in a pair of improved coupling members for placing the circulation coils of the water heater in connection with a storage tank. Both of these coupling members provide union connections between the circulation coils and the coupling member by means of which the coils may be easily and quickly removed and replaced in the event of failure of the coils. One of the coupling members is also adapted 30 for reception of a thermostat and eliminates the necessity of a separate opening and tapping in the storage tank for this element.

35 The advantages of this arrangement are first of all a reduction in the cost of manufacturing a heating system of this type by elimination of the extra tank tapping for 40 reception of the thermostat.

45 Another advantage of this arrangement is that the circulation coils, which are the parts of the heater which are most apt to fail, may be readily removed and replaced by simply unscrewing the union connections by means of which they are connected to the coupling members. This construction also results in adding considerably to the life of the coils by eliminating the brazed joint of the coils, which has a tendency to weaken the coils at this point and render them more susceptible to the corrosive action of the sulphuric acid which is apt to be formed from the products of combustion of the burning gas.

50 This application is a continuation in part of my copending application Serial No. 257,916 filed February 28, 1928, and differs therefrom in that the coil coupling disclosed herein is provided with a shielded passageway for reception of the thermostat and furthermore in that the present coupling is adapted to be directly and removably connected to ends of the tubing of the heater coil thereby eliminating the need of the brazed coil coupling shown in my copending application above referred to.

55 Referring to the drawings; Fig. 1 is a side elevational view in section of a water heater taken on line 1—1 Fig. 2, showing one form of my improved coupling member. Fig. 2 is a section taken on line 2—2 Fig. 1, showing the upper coupling member of the heater coils. Fig. 3 is a section similar to Fig. 2 showing the lower coupling member.

60 The enlarged view of the water heater shown in Fig. 1, shows in part a storage tank 1, which is adapted for communication with, and connection to the circulation coils 2. The tank 1 is provided with heat insulating material 3 which is held in position against the side of the tank by means of an outer casing 4. The upper and lower terminating portions of the heater coils 2 are placed in communication with the tank 1 by means of coupling members 5 and 6, respectively. The upper coupling member 5 is received in the threaded opening 7 in the side of the tank and a similar tapping 8 is provided for the reception of the lower coupling member 6.

A heater jacket 9 of the conventional type provides a housing for the circulation coils 2. This jacket is provided with a top 10 having a vent 11 for the escape of the products of combustion from the heater. Heat is applied to the circulating coils by the gas burner 12 that is mounted by means of a ground and tapered connection 13 on the base member 14 which is secured to the lower 15 extremity of the heater jacket 9 in any suitable manner such as by the bolts 15. The burner 12 is a blue flame gas burner, having a gas and air mixing tube not shown, which is in communication with the central passage 16 of the heater base that communicates with the burner 12.

The lower coupling member 6 is a Y shaped connector, formed from a single casting and is externally threaded at 17 for reception in the tank tapping 8. The branch elements of the member 6 are externally threaded at 18 and 19 for reception of the union nuts 20 and 21, respectively. Tapered ends 22 and 23 are formed on the coupling member 6 adjacent the threaded portions 18 and 19 respectively.

The ends of the coils 2 are flanged as at 24 and 25 and are adapted to be detachably secured to the coupling member 6 by means 20 of the union nuts 20 and 21 respectively.

The upper coupling member 5 is provided with an externally threaded portion 26, adapted for threaded engagement with the tank tapping 7. The member 5 has a pair 35 of branch ports provided with tapered ends 27 and 28 which are adapted to provide a fluid-tight connection with the complementary flanged ends 29 and 30 of the heater coils 2. This connection is made by a pair of union 40 nuts 31 and 32 which are threadably received by the externally threaded branches 33 and 34 of the coupling member 5. By this arrangement a union connection is provided between the coupling member 5 and the coils 2 which may be removed from this coupling by unscrewing the nuts 31 and 32.

The supply of gas to the burner 12 is controlled by means of a thermostat 35 which is internally threaded at 36 for connection to 50 a source of gas supply. The externally threaded portion 40 of the thermostat 35 is received in the screw threaded opening 37 of the coupling member 5. The expansion element 38 of the thermostat is protected and 55 shielded from the incoming hot water passing through the coupling, by means of an angularly disposed tubular sheath 39 integrally formed in the coupling member 5. The thermostat receiving passageway defined by the 60 sheath 39 terminates at its outer end in the threaded opening 37 and at its inner end it is in communication with the interior of the tank. By arranging the sheath 39 on an angle with respect to the main passageway of 65 the coupling, the expansion element 38 of the

thermostat may be located to one side of the stream of hot water flowing into the tank.

The purpose and function of the sheath 39 is to shield the thermostat from direct contact with the incoming hot water from the heater coils and to make it responsive to the water within the tank rather than the water which is just discharged from the heater and which is apt to be at a much higher temperature than the average temperature of the water in the tank at the level of the coupling 5. The coupling members 5 and 6 are also provided with hexagonal wrench engaging faces 41 and 42 which provide a means for their application to the storage tank 1.

In assembling my improved heater the coupling members 5 and 6 are first secured in the tappings 7 and 8 respectively. The heater coils 2 are then connected to the coupling member 5 and 6 and the heater jacket, top and base are added to complete the assembly of this unit. It is apparent from the preceding that the coils 2 may be readily removed and replaced with a minimum of work and that it is not necessary to scrap the coil 90 couplings each time a coil is replaced as is the case where these elements are brazed to the coils.

Furthermore, it is to be understood that the particular forms of apparatus shown and described, and the particular procedure set forth, are presented for purposes of explanation and illustration and that various modifications of said apparatus and procedure can be made without departing from my invention as defined in the appended claims.

I claim:

1. In a water heater, the combination of a storage tank having a pair of openings formed therein, one of which is located in the side of the tank, and means for establishing communication between said openings including a heating coil and an integrally formed fitting, said fitting being detachably received in the hot water inlet opening of said tank and detachably connected to said coil whereby said coil is supported closely adjacent to the side of the tank and placed in direct communication therewith by means of a relatively large and short horizontally disposed passageway in said fitting, said fitting being further provided with a second passageway formed in said first named passageway, and a thermostat extending through said second passageway into said tank, whereby said thermostat is shielded from the hot water passing through said fitting into said tank.

2. In a water heater, the combination of a storage tank having a pair of openings formed therein, one of which is located in the side of the tank, and means for establishing communication between said openings including a heating coil and an integrally formed fitting, said fitting being detachably

secured in the hot water inlet opening of said tank and detachably connected to said coil whereby said coil is supported closely adjacent to the side of the tank and placed in 5 direct communication therewith by means of a relatively large and short horizontally disposed passageway formed in said fitting, said fitting being further provided with a second horizontally disposed passageway formed in 10 said first named passageway and traversing the same on an angle, and a thermostat extending through said second passageway angularly into said tank whereby said thermostat is shielded from incoming hot water 15 within said fitting and is out of the path of hot water entering said tank.

3. In a water heater, the combination of a storage tank having a pair of openings formed therein one of which is located in the 20 side of the tank, and means for establishing communication between said openings including a heating coil and an integrally formed fitting connected to the hot water inlet of said tank, said fitting having a pair of 25 passageways communicating with the interior of the tank one of which is provided to establish communication between said coil and tank, and a thermostat received in the other of said passageways and projecting in- 30 to said tank to one side of said first named passageway whereby said thermostat is supported in the tank to one side of the water stream induced by said coil and is shielded from incoming hot water in said fitting.

35 4. In a water heater, the combination of a storage tank having a pair of openings formed therein one of which is located in the side of the tank, and means for establishing communication between said openings including a heating coil and an integrally formed fitting connected to the hot water 40 inlet opening of said tank, said fitting having a pair of ports in communication with the interior of the tank when said fitting is secured in place in said tank, one of said 45 ports communicating with said heater coil by way of a relatively large and short passageway and the other of said ports communicating with a second passageway traversing said 50 first named passageway on an angle and terminating at the side of said fitting opposite to said pair of ports, and a thermostat in said second passageway, whereby said thermostat is shielded from incoming hot water in said fitting and is out of the stream of incoming 55 hot water in said tank.

In testimony whereof I affix my signature.
ARTHUR FRIEDMAN.
